ENCLOSURE

Joseph A. Volk, Wilton, Conn.

Application January 28, 1938, Serial No. 187,440

13 Claims. (Cl. 135—5)

The present invention relates to devices for winding and unwinding sheets or walls of flexible material, for example, curtains.

More particularly, the invention is concerned with devices for forming a removable compartment or enclosure which is adapted to be installed in a portion of a store adjacent the entrance and whereby such enclosed portion is separated from the main part of the store so that deliverymen who are allowed to open the entrance door with a pass key, can deposit their goods within such enclosure without being able to enter the main part of the store itself.

Various kinds of enclosures or compartments of this general type have already been proposed. Some of these known structures are so designed that they can be removed entirely from their intended place of use and be stored away during business hours. Usually, they are difficult to be reassembled and installed and require considerable time and effort for such assembly and installation aside from the space they assume when not in use.

Other structures used by the prior art are of the retractable type in which the elements which ultimately form the walls of the enclosure are suspended from the ceiling and consist, for example, of series of bars which by means of a motor and a system of pulleys are lowered to form a lattice. This type of structure has the great disadvantage that any person within the enclosure attempting to steal goods from the store only needs to pass his arm or a suitable tool as commonly used in stores for taking goods from high shelves, through the latticework of the enclosure to grasp and withdraw through the openings of the walls any goods within reach and of sufficiently small size. Furthermore, these retractable lattice walls have to consist of metallic bars, for example, of steel, so that considerable machinery and power is required for raising and lowering the same.

The present invention relates to a delivery enclosure of the retractable type and it is the primary object of the invention to construct such enclosure which retains all the advantages of the prior art but overcomes all its disadvantages.

Another object of the present invention consists in the construction of an enclosure which prevents any unauthorized person from entering the store proper and the passage of grasping tools through openings in the walls thereof.

Another object of the invention resides in forming an enclosure, the walls of which can be set up or retracted simultaneously.

Another object consists in constructing such an enclosure, the walls of which are of flexible sheet material which can be wound or unwound simultaneously.

Still another object resides in forming a plurality of curtains which are angularly disposed to one another and are wound upon or unwound from a plurality of shafts forming a top frame.

Another object of the invention resides in forming an enclosure or compartment, the walls of which can be pivoted relative to a fixed support such as a wall or door frame so as to assume various shapes and positions relative to such fixed support.

Another object consists in constructing an enclosure, the walls of which can be securely locked to one another and to the ground, and the operating mechanism of which is suspended from a wall and from the ceiling of a store or similar room so that any access to the store except by a person authorized to unlock and open the enclosure is effectively prevented.

Another object of the present invention resides in designing a delivery enclosure which can be operated manually and which is of relatively inexpensive and simple construction.

Features of the invention consist in: universal means for connecting and rotating the shafts of the top frame of the enclosure; a plurality of roll-curtains which, when in unwound condition, can be securely connected with one another; means for hinging the walls of the enclosure to a fixed support such as a wall and for pivoting the entire enclosure relative to such a fixed support; means for changing the shape, position and capacity of such enclosure; means for locking the walls of the enclosure relative to each other, relative to the fixed support or wall and relative to the ground or floor by the use of a single locking device, such as a padlock; and means for interlacing the individual walls of the enclosure with one another.

These and other objects, features and advantages of the present invention will be apparent in greater detail from the following detailed description and the accompanying drawings, in which:

Figure 1 shows a reduced top view of the enclosure device according to the present invention applied to the front walls of a store.

Fig. 2 is a side view partially in section taken along lines 2—2 in Fig. 1.

Fig. 3 is an enlarged fragmentary side view similar to Fig. 2.

Fig. 4 is a fragmentary section taken along lines 4—4 of Fig. 1.

Fig. 5 is a fragmentary section similar to Fig. 4 but showing another part of the enclosure device.

Fig. 6 is a reduced rear view.

Fig. 7 is a fragmentary section taken along lines 7—7 of Fig. 4.

Fig. 8 is a fragmentary section taken along lines 8—8 of Fig. 2.

Before describing the present improvements and mode of operation thereof in detail it should be understood that the invention is not limited to the details of construction and arrangement of parts shown in the accompanying drawings, which are merely illustrative of the present preferred embodiments, since the invention is capable of other embodiments, and the phraseology employed is for the purpose of description and not of limitation.

As shown in Fig. 1, a top frame 10 consisting of a plurality of interconnected tubular shafts 11 may be secured by means of hinges 12 to the jambs 13 of the entrance door of a store so that the top frame 10 assumes substantially the shape of a parallelogram and can swing or turn as a unit about the hinges 12 and relative to the door 14; or the hinges 12 may be secured in various other places of the front walls 15 as indicated in dotted lines in Fig. 1; or one or both hinges may be secured to one or both side walls 16, so that the frame 10 may assume various angular shapes.

The hinges 12 shown in the drawings preferably consist of balls 17 rigidly secured to the ends of shafts 18 and 19 and held within sockets 20 which, in turn, are secured to the door jamb 13 or to the walls a short distance below the ceiling, so that the shafts 18 and 19 can rotate about their own axes and pivot relative to the sockets.

Shafts 18 and 19 are provided at their rear ends with balls 21 which are secured by means of sockets 22 to stubs 23 and 24. Each of balls 21 is provided with a circumferential groove 25 in which a pin 26 secured in socket 22 engages so as to permit pivotal movement of shafts 18 and 19 relative to stubs 23 and 24 in all directions. Shaft 27 is likewise provided with short stubs 28 and 29. As shown particularly in Fig. 3, stubs 23 and 28 of shafts 18 and 27, respectively, extend into a housing 30, the walls 31 and 32 of which serve as bearings for the stubs, and carry at their free ends interengaging bevel gears 33 and 34, while stubs 24 and 29 of shafts 19 and 27, respectively, extend into a housing 35 and carry at their free ends worm gears 36 and 37, respectively, as shown in Fig. 7 of the drawings. A shaft 38 which is provided at its lower end with a hook 39 extends into housing 35 and has secured to its upper end a worm 40 which is interposed between and engages with gears 36 and 37. Thus, if the hook 39 is rotated by a suitable hooked rod or the like, shafts 18 and 19 are turned in opposite directions to each other and all three shafts 18, 19 and 27 are rotated simultaneously.

Housings 30 and 35 are preferably secured to the ceiling 41 of the store by means of a suspension 42 comprising a rail 43 which is passed through eye bolts 44 and is secured thereto by cotter pins 45, passing through bores 46 in said rail. A bar 47, which is rigidly secured to each of housings 30 and 35, is provided with a bifurcated upper end 48 and is adjustably secured 75 to rail 43 by a collar 49 positioned intermediate

the bifurcations, so that its position on rail 43 can be changed in lateral directions thereof.

Secured to shafts 18, 19 and 27 are sheets or curtains 50, 51 and 52, respectively, of flexible material of any suitable type which can be wound upon a shaft and unwound therefrom. The particular manner of securing the sheets 50, 51 and 52 to the shafts depends on the type of material used. In the embodiment of the invention shown in the drawings, these sheets or curtains are intended to consist of fabric, such as canvas, and the sheets are secured at the upper end thereof to the respective shafts 18, 19 and 27 by tacking, gluing or the like.

The lower ends of curtains 50 and 51 are provided with looped portions 53 through which tubular rods 54, 55 and 56, respectively, are passed. As shown in Fig. 3, rods 54 and 55 of the lateral curtains 50 and 51 are open at their forward ends and provided with a ring or eye 57 at their rear ends, while rod 27 of the intermediate curtain 52 has a similar ring or eye 58 secured to each end. The eyes 53 of the intermediate rod 27 are connected to the eyes 57 of the lateral rods 18 and 19 by links 59.

Studs 60 are rigidly fixed by means of brackets 61 to the front or side walls 15 and 16 near the floor 62 in a position corresponding to that of hinges 12, and are designed to enter the open ends of rods 18 and 19. Bores 63 are provided in rods 18 and 19 near the rear ends thereof and adjacent curtains 50 and 51. Bolts 64 which have an eye 65 at their upper ends are passed through said bores 63 and a collar 66, and are screwed into sockets 67 which are sunk into the floor 62 and secured thereto by screws or nails 68. As shown in Fig. 3, the position of bores 63 and sockets 67 is such that the forward end of rods 18 and 19 is located closely adjacent the brackets 61 when bolts 64 are passed through bores 63 and 40 are screwed into sockets 67. Since rods 18, 19 and 27 are interconnected by links 57, 58 and 59 the screwing of bolts 64 into sockets 67 serves to secure all of said rods in substantially fixed position and the unwound curtains to the floor. 45

Various types of means may be designed for interlocking the sides of the adjacent curtains and for locking the forward side of the lateral curtains to the walls of the store. For example, the adjacent sides of the curtains may be provided with a series of slide fastener elements of any well-known type which may be interconnected or separated by means of the usual sliding element which may be locked to the bolt 64 by any suitable locking means. 55

In the particular embodiment of the invention shown in the drawings, curtains 50, 51 and 52 are provided near their lateral edges with eyelets 69. One or more cords or cables 70 are passed through the eyelets 69 of the adjacent curtains so as to interlace the same. In order to prevent unauthorized persons from loosening the cables, they may be passed through the eyelets from the opposite ends of the curtains toward the middle thereof. The free ends 71 of the cables 60 used to interlace the two sides of the rear curtain 52 to the respective side curtains 50 and 51 are then passed across the middle of curtain 52 and tied to each other, as shown in Fig. 6, or secured to each other in any other manner. 65

For securing the side curtains 50 and 51 to the wall, eye bolts 76 are screwed into the latter at intervals substantially corresponding to the intervals between the eyes 69 in the front ends of curtains 50 and 51. However, the looped por- 75

tions 12 of these eye bolts 16 are of smaller diameter than the diameter of the eyes 69 in the curtains so that the latter can be passed over the loops 72, as shown in Fig. 8 of the drawings. 5
6 Two rods 73, each of which has an eye portion 74 at one end, are then passed near the middle height of the curtains upwardly and downwardly, respectively, through the loops 72 and a padlock 75 or the like is inserted through the eyes 14 to 10
10 lock the rods 73 against withdrawal. Obviously, the rods 73 must be of stiff but sufficiently flexible material to permit them to be bent slightly for their insertion in the loops 72.

In place of the pair of rods 73 at each of the 15 curtains 50 and 51, a single rod may be used. However, due to its length, such a rod would have to be quite flexible to permit its insertion into the loops 72, and the lock should then be passed through an eye at the end of the rod and through 20
20 the lowest loop 72'.

As already indicated, all of the curtains can easily be raised and lowered simultaneously when separated from each other by turning the crank 39 in one direction or another. After the curtains have been lowered, the bolts 64 are passed 25 through the rods 18 and 19 and screwed into sockets 67 and then the cords or cables 70 are passed through the eyelets 69 of the adjacent sides of the curtains and through the eyes 65 of 30
30 bolts 64 and tied or locked to each other. Thereupon, the eyelets at the forward ends of curtains 18 and 19 are passed over the corresponding eye bolts 16, the rod or rods 73 are threaded into the loops 72 of these eye bolts, and padlocks 75 are 35 inserted into the eyes 14 of the rods 73 and locked.

Inasmuch as the eye bolts 16 are turned inwardly of the enclosure, as shown in Fig. 8 of the drawings, the rods 73 and padlocks 75 can be inserted and removed from the inside of the 40 enclosure after every other locking element has been secured.

By changing the position of hinges 12, any desirable shape and size of the enclosure may be obtained. Furthermore, the entire enclosure may be 45 placed at various angles relative to the front wall so that it may be swung and secured clear of any tables, cabinets, piles of goods or other articles, as indicated for example by numeral 77 in Fig. 1 of the drawings.

50 Variations and modifications may be made within the scope of this invention and portions of the improvements may be used without others.

Having thus described the invention, what is claimed as new is:—

55 1. An enclosure comprising at least two shafts in angular position to one another; at least one sheet of flexible material secured to one of said shafts; means for connecting said shafts to one another to permit angular motion of said shafts relative to each other in any direction; and means for rotating said shafts simultaneously, 60 for winding and unwinding said sheet.

65 2. An enclosure comprising at least two shafts in angular position to one another; at least one sheet of flexible material secured to one of said shafts; a fixed element; means for hingedly securing at least one of said shafts at one end to the fixed element; means for connecting said shafts to one another to permit angular motion of said shafts relative to each other in any direction; and means for rotating said shafts simultaneously, for winding and unwinding said sheet.

70 3. An enclosure comprising at least two shafts in angular position to one another; at least two sheets of flexible material each secured to one

of said shafts; means interposed between said shafts for winding said sheets simultaneously upon said shafts and for unwinding them simultaneously therefrom; and a universal joint interconnecting one of said shafts with said means. 5

4. An enclosure comprising at least two shafts; fixed supporting means; means for hingedly securing said two shafts to said fixed supporting means; a third shaft; means for pivotally connecting said two shafts to the third shaft; at least 10 three curtains each secured to one of said shafts; and means for winding said curtains simultaneously upon said shafts and for unwinding them simultaneously therefrom.

5. An enclosure comprising a top frame including at least three shafts; at least three sheets of flexible material each secured to one of said shafts; means for connecting said shafts to permit angular motion of said shafts relative to each other in any direction; means for securing said shafts in angular position to one another; means for maintaining said top frame in elevated position above the floor; and means for winding said sheets simultaneously upon said shafts and for unwinding them simultaneously therefrom. 15 20
25

6. An enclosure comprising a top frame including at least two shafts in angular position to one another; at least two sheets of flexible material each secured at one end to one of said shafts; fixed supporting means; means for securing each of said shafts at one end to said fixed supporting means; means interposed between said shafts for rotating said shafts simultaneously for winding said sheets thereupon and for unwinding them therefrom; a universal joint interconnecting one of said shafts with said rotating means; and means for interconnecting the adjacent sides of said sheets when in unwound position. 30 35

7. An enclosure comprising a top frame including at least two shafts; a third shaft; at least three sheets of flexible material each secured at one end to one of said shafts; fixed supporting means; means for securing two of said shafts at one end to said fixed supporting means; means 40 for connecting said two shafts to the third shaft to permit angular motion of all of said shafts relative to each other in any direction; means for rotating all of said shafts simultaneously for winding said sheets thereupon and for unwinding them therefrom; means for interconnecting the adjacent sides of said sheets when in unwound position; and means for locking said sheets to the floor. 45 50

8. An enclosure comprising a top frame including at least two shafts; a third shaft; at least three sheets of flexible material each secured at one end to one of said shafts; fixed supporting means; means for securing two of said shafts at one end to said fixed supporting means; means for connecting said two shafts to the third shaft to permit angular motion of all of said shafts relative to each other in any direction; means for rotating all of said shafts simultaneously for winding said sheets thereupon and for unwinding them therefrom; and means including at least one rod secured to the other end of at least one of said sheets; means for interconnecting the adjacent sides of said sheets when in unwound position; and means for locking said rod to the floor. 55 60 65
70

9. An enclosure comprising a top frame including at least two shafts; a third shaft; said shafts being angularly disposed to one another; at least three sheets of flexible material each 75

- secured at one end to one of said shafts; fixed supporting means; means for connecting said two shafts to the third shaft to permit angular motion of all of said shafts relative to each other 5 in any direction; means for rotating all of said shafts simultaneously for winding said sheets thereupon and for unwinding them therefrom; at least three rods each secured to the other end of said sheets; means for locking said rods 10 to the floor when said sheets are in unwound position; and means for interconnecting the adjacent sides of said sheets with one another and with said locking means.
10. An enclosure comprising a top frame including at least two shafts; a third shaft; at least three sheets of flexible material each secured at one end to one of said shafts; fixed supporting means; means for securing two of said shafts at one end to said fixed supporting 15 means; means for connecting said two shafts to the third shaft to permit angular motion of all of said shafts relative to each other in any direction; means for rotating all of said shafts simultaneously for winding said sheets thereupon and 20 for unwinding them therefrom; at least three rods each secured to the other end of said sheets; means for interlocking the adjacent ends of said rods; means for locking said rods to the floor when said sheets are in unwound position; and 25 means for interlocking the adjacent sides of said sheets.
11. An enclosure comprising a top frame including at least two shafts; a third shaft; said shafts being angularly disposed to one another; fixed supporting means; means for hingedly securing one end of each of said two shafts to said fixed supporting means; means for connecting the other end of each of said two shafts to the 30 third shaft to permit angular motion of all of
- said shafts relative to each other in any direction; at least three sheets of flexible material each secured at one end to one of said shafts; means on one shaft for rotating all of said shafts simultaneously for winding said sheets upon said shafts and for unwinding them therefrom; at least three rods each secured to the other end of said sheets; means for interconnecting the adjacent ends of said rods; means for locking said rods to the floor when said sheets are in unwound position; and means for interlacing the adjacent sides of said sheets with one another and with said locking means. 5
12. An enclosure comprising a top frame including at least two shafts; a third shaft; means for connecting one end of each of said two shafts to the third shaft to permit angular motion of all of said shafts relative to each other in any direction; at least three sheets of flexible material each secured at one end to one of said shafts; 15 means on one shaft for rotating all of said shafts simultaneously for winding said sheets upon said shafts and for unwinding them therefrom; fixed supporting means; and means for securing the other end of each of said two shafts to said supporting means and for adjusting said shafts at various angles relative to said fixed supporting means. 20
13. An enclosure comprising a top frame including at least two shafts; a third shaft; at least one sheet of flexible material secured to one of said shafts; means for connecting one end of each of said two shafts to the third shaft and for adjusting said shafts at various angles toward one another; and means for rotating said shafts simultaneously for winding and unwinding said sheet. 25

JOSEPH A. VOLK.
